FIG. 1 is a front perspective view of an exemplary fountain of the present invention;

FIG. 2 is a front elevation view of the exemplary fountain of FIG. 1;

FIG. 3 is a rear elevation view of the FIG. 1 embodiment;

FIG. 4 is a right side view of the FIG. 1 embodiment;

FIG. 5 is a left side view of the FIG. 1 embodiment;

FIG. 6 is a top plan view of the FIG. 1 embodiment;

FIG. 7 is a bottom plan view of the FIG. 1 embodiment;

FIG. 8 is an exploded perspective view of the FIG. 1 embodiment; and,

FIG. 9 is an environmental perspective view of the FIG. 1 embodiment.

The broken lines are for illustration only and form no part of the claimed design.
